UNITED STATES PATENT OFFICE

EDWARD A. SATTLER, OF BUFFALO, NEW YORK, ASSIGNOR TO GEORGE J. SATTLER, OF BUFFALO, NEW YORK

ARTIFICIAL DENTURE

Application filed August 10, 1929. Serial No. 384,815.

This invention relates to an artificial denture and has the object to provide a mounting for this purpose whereby artificial teeth are held securely and reliably against displacement while in use without showing any of the mounting from the front side of the teeth and still permit of readily replacing a worn or broken tooth when this becomes necessary.

In the accompanying drawings:

10 Figure 1 is a perspective view of one of the anterior artificial teeth constructed in accordance with my invention.

Figure 2 is an elevation of the same view from the inner or lingual side thereof.

15 Figure 3 is a side elevation thereof.

Figure 4 is a vertical section taken on line 4—4 Fig. 2.

Figures 5 and 6 are horizontal sections taken on the correspondingly numbered 20 lines in Fig. 2, looking upwardly and downwardly respectively.

Figure 7 is a perspective view of one of the posterior artificial teeth embodying my improvements.

25 Figures 8 and 9 are perspective views of the backing of the artificial tooth mounting containing my invention and viewed respectively from the lingual and buccal side of the same.

30 Figure 10 is an elevation of the combined artificial tooth and backing of the mounting constructed in accordance with my improvements.

Figure 11 is a vertical section of the same 35 taken on line 11—11 Fig. 10, but including the supporting bar or bridge of the mounting.

40 Figures 12 and 13 are horizontal sections taken on lines 12—12 and 13—13 respectively in Fig. 10, but including the supporting bar or bridge of the mounting.

45 Figure 14 is a fragmentary face view of the teeth of one jaw, partly in section, showing the manner of mounting a plurality of artificial supply teeth on a plurality of natural abutment teeth.

Figure 15 is an elevation thereof viewed from the inner or lingual side thereof.

50 In the following description similar char-

acters of reference indicate like parts in the several figures of the drawings.

The numeral 20 represents the body of an artificial tooth which may be made in various shapes of porcelain, as usual, in any suitable and well-known manner, and which presents uninterrupted buccal occlusal and the gingival surfaces 21, 22, 23 respectively on no parts of which the mounting is visible from the outer or front side of the artificial teeth inasmuch as this mounting only couples with the artificial teeth on the rear, inner or lingual surface 24 of the same. In Figs. 1—4, 10 and 11 this body has the form of an anterior tooth while in Fig. 7 the same has 65 the form of a posterior tooth.

For the purpose of this invention the lingual surface of the artificial tooth is provided between the cusp or incisal edge and gingival surface with an anchorage which is 70 constructed as follows for receiving a backing of corresponding form.

The numeral 25 represents an upright tenon or tongue projecting inwardly from the central part of the lingual side of the 75 body and formed integrally therewith. This tenon is provided on its upper part with an inclined inner face 26 and two parallel upright faces 27 on opposite sides of the inner inclined face 26, and the lower part of 80 this tenon has a vertical inner face 28 and two undercut inclined faces 29 on opposite sides of the inner face 28.

It is to be understood that in using the 85 terms "upper" and "lower" in the above description the same refers to the lower teeth shown in the drawings and that these terms must be reversed when describing the upper teeth but in this description the terms "upper" and "lower" will be used to describe 90 both kinds of teeth as a matter of convenience.

The central part of the lingual side of the 95 artificial tooth around the tenon is set back so as to produce a cavity having upper and lower parallel horizontal walls or shoulders 30, 31 at the upper and lower ends of the tenon and outwardly converging upright walls or shoulders 32 arranged on opposite sides of the tenon. The upright side walls 100

27 of the tenon and the adjacent walls 30, 31 and 32 of the body 20 form two recesses 40 on opposite sides of the tenon, said walls 32 which form the bottoms of these recesses converging forwardly toward the front side of the tooth, as shown in Figs. 5 and 6. The upper shoulders or walls 31 extend partway across the upper side portions of the inclined wall 26 and the lower shoulders are extended toward each other so that they meet and form a continuous wall along the vertical part 28 of the tenon.

On the upper part of the lingual side of the tooth the same is provided with a socket 33 which is formed partly in the upper part of the tenon and partly in the adjacent upper part of the body, and opens inwardly. This socket is generally of keystone shape and provided with a vertical bottom 34, horizontal upper and lower walls 35, 36, and two inclined side walls 37 which converge from the upper toward the lower end of the tooth.

Fitting against the central part of the inner side of the tooth so as to embrace the tenon thereof and the various walls of the cavity around the tenon, and the socket across the tenon and body is a backing 53 which is preferably made of any suitable kind of sheet metal, such as gold. As best shown in Figs. 10-14, this backing is provided on its outer or front side with a central upright socket 38 which receives the body tenon of the artificial tooth, two wings 39 on opposite sides of the socket 38 and 45 adapted to project into the recesses 40 of the tooth body on opposite sides of the tenon, and a tenon or tongue 41 arranged above the socket 38 and adapted to project into the body socket 33.

40 The socket 38 conforms to the shape of the body tenon and is provided with an upper inclined rear wall 42 adapted to engage the inclined upper wall 26 of the body tenon, a lower vertical rear wall 43 engaging with the lower vertical face 28 of the body tenon, two upper upright side walls 44 engaging with the opposite vertical upper sides 27 of the body tenon, and two lower inclined side walls 45 engaging with the lower inclined undercut walls 29 of the body tenon. Each of the wings of the backing comprises an inclined front wall 46 engaging the inclined back wall 32 of the respective body recess 40, an upper horizontal wall 47 engaging with the upper wall 30 of one of the recesses 40, and a lower horizontal wall 48 engaging the corresponding lower horizontal wall 31 of the respective body recess 40. The tongue 41 has a vertical front wall 49 engaging the vertical back 34 of the socket 33, horizontal top and bottom walls 50, 51 engaging with the top 35 and bottom 36 of the body socket 33, and inclined side walls 52 engaging with the correspondingly inclined side walls 37 of the body socket.

The metal backing and the artificial tooth are secured to each other by a cement of any suitable or well-known character applied to the opposing surfaces of these members. This backing is secured to the outer side of a horizontal bridge 54 which may be constructed of any suitable metal preferably gold, by soldering, brazing or otherwise forming a practically integral joint between these members, and the bridge in turn is supported in any suitable manner on the jaw. As shown in Figs. 14 and 15 of the drawings two artificial teeth are arranged to alternate with three natural teeth 55, 56, 57 and the respective artificial teeth are mounted relative to the natural teeth in this instance by providing the central natural tooth 56 and the rear natural tooth 57 with caps 58, 59 to which the bridge 54 is secured by soldering, brazing or otherwise so that the several backings, the bridge and the caps form a supporting unit for the artificial or supply teeth on the capped natural teeth which latter serve as the abutments for this purpose.

When the artificial teeth are thus mounted they are securely anchored against displacement under strains to which they are normally subjected, these strains being mainly either vertically when biting or circumferentially when grinding, but least likely in a direction transversely to one another. When subjected to vertical and circumferential strains the artificial tooth is held securely on the backing by the interlocking tenon and sockets of the artificial tooth and the backing, and also the interlocking wings and recesses of these members.

Any strains which tend to tilt the artificial tooth either forwardly or backwardly about a horizontal axis, or to turn or twist the same about a vertical axis, are resisted by the inclined co-operating surfaces formed between lower parts of the tenon on the tooth body and socket in the backing and between the upright sides of the backing tenon and the socket in the tooth body, which inclined surfaces form undercut engaging areas having the effect of hooks whereby the tooth body and backing are securely anchored to each other and interlocked in a manner which positively prevents their separation when subjected to tilting or twisting strains. It is therefore possible to use the artificial teeth as effectively under all conditions as natural teeth without liability of a break down and at the same time avoid exposure of any part of the mounting on the front side of the artificial teeth.

This mounting is very strong and durable, not liable to get out of order, and can be manufactured at comparatively low cost. When repairing of an artificial tooth becomes necessary this can be readily accomplished by loosening the cement and withdrawing the tooth horizontally from the backing and re-

placing the same by a new one in the reverse manner, and then securing the same by cement.

I claim as my invention:—

- 5 1. An artificial denture mounting comprising a tooth body provided on its rear side with a tenon the upper parts of whose sides are vertical and the lower parts thereof inclined toward each other, and a backing having a socket provided with side walls the upper parts of which are vertical and engage the vertical side faces of said tenon and the lower parts of which incline toward each other and engage with the inclined lower parts of the sides of said tenon, and said body being provided on opposite sides of said tenon with recesses having inclined bottoms converging forwardly and said backing having wings on opposite sides of said socket, the front sides of which are inclined and engage with the correspondingly inclined bottoms of said recesses.
- 10 2. An artificial denture mounting comprising a tooth body provided on its rear side with a tenon the upper parts of whose sides are vertical and the lower parts thereof inclined toward each other, and a backing having a socket provided with side walls the upper parts of which are vertical and engage the vertical side faces of said tenon and the lower parts of which incline toward each other and engage with the inclined lower parts of the sides of said tenon and said body being provided on the upper part of its rear
- 15 face with a socket having downwardly converging sides, and said backing being provided on the upper part of its front face with a tenon having downwardly converging sides engaging with the downwardly converging sides of the body socket.
